CLAIM

I claim the ornamental design for a shoe sole, substantially as shown and described.

DESCRIPTION

FIG. 1 is a left side view of a shoe sole showing my design; FIG. 2 is a right side view of the shoe sole shown in FIG. 1; FIG. 3 is a bottom view of the shoe sole shown in FIGS. 1-2; FIG. 4 is a frontal view of the shoe sole shown in FIGS. 1-3; and,

FIG. 5 is a rear view of the shoe sole shown in FIGS. 1-4. The surfaces of the shoe sole that are not shown in the drawings, or described in the specification, form no part of the claimed design.

Surfaces and features indicated by broken lines are for illustrative purposes only and form no part of the claimed design.
